(57) **CLAIM**

The ornamental design for a spray gun for paint, as shown and described.

DESCRIPTION

FIG. 1 is a front perspective view of a spray gun for paint illustrating our new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken line showing is included for the purpose of illustrating and forms no part of the claimed design.
